Atty.

UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

FOUR-HOLE SEW-ON BUTTON.

Application filed November 16, 1925. Serial No. 69,322.

To all whom it may concern:

Be it known that I, FRANKLIN R. WHITE, a citizen of the United States, residing at Waterbury, in the county of New Haven and State of Connecticut, have invented certain new and useful Improvements in Four-Hole Sew-On Buttons, of which the following is a specification.

My invention relates to new and useful improvements in sew-on buttons of the four-hole type and has for an object to so arrange the hub of the button and the holes within the hub that the button may be placed in a button sewing machine and properly positioned and guided to a point beneath the needles so that the holes will be directly beneath the path of the needles.

The present application is a companion one of four others filed of even date here-with, and is similar in most respects to one bearing Serial Number 69,321, filed November 16, 1925, but in this instance, the holes are arranged in different relationship in the hub as the needle or needles of the button attaching machine (not shown), may be ar-ranged in a different manner.

Another object of the invention is to pro-vide a button wherein the end of the hub may be square as shown in the preferred form, or may have two parallel sides and rounded opposite ends, the parallel sides in each instance forming a projection to fit within a chute or track of a sew-on button machine.

With these and other objects in view, the invention consists in certain new and novel arrangements as will be hereinafter more fully described and pointed out in the claims.

40 In the drawings showing a preferred and slightly modified form,

Fig. 1 is a top plan view of my improved button.

Fig. 2 is a sectional view taken on line 45 2-2 of Fig. 1.

Fig. 3 is a rear view of the button.

Fig. 4 is a top plan view similar to Fig. 1, but showing a slightly modified form.

Fig. 5 is a sectional view taken on line 50 5-5 of Fig. 4, and

Fig. 6 is a rear view of the modified form.

Referring now more particularly to the drawings, and to Figs. 1, 2 and 3, there is shown a button comprising a body portion 1,

having the rim 2 merging therewith, while 55 the face of the button is centrally depressed as at 3. Formed integral with the body por-tion is the circular hub 4 which is cut or formed so that it will be square at its lower end. In other words, small side walls 5, 60 6, 7 and 8 are formed so that the end of this hub may properly fit within a chute (not shown) and be guided in its movement to a point beneath the needles.

Formed in this hub are the four holes 9 65 and the location of these holes distinguish the application from one of the companion applications, bearing Serial No. 69,321. In the present instance, if two lines are drawn to intersect at right angles at the center 10, 70 and the lines are drawn at right angles to the sides of the hub, each line will also intersect the center of two of the holes 9.

The four holes are all equi-distant from the center 10, and one hole will be located 75 adjacent each of the four sides 5, 6, 7 and 8.

Referring now to the modified form, Figs. 4, 5 and 6, there is also shown a button comprising a body portion 11, with the rim 12, the hub 13 and the upper face of the button 80 depressed as at 14.

This hub 13, instead of being square at its ends, however, has two portions cut away to form but two parallel side walls 15 and 16 which merge with the rounded ends of 85 the hub 17 and 18.

Four holes 19 are shown extending through the hub, all equi-distant from the center 20, and in a like manner, if two lines are drawn perpendicular to each other 90 and intersecting at the center 20, each line would intersect the centers of two of the holes as in the preferred form.

From the foregoing it will be seen that if the preferred type of button is used, the button may be in any one of four positions when it enters the chute as two of the side walls will be guided in a track, and if the modified form is used, the button may enter the chute from one of two positions, as the 100 opposite ends are similar. It will be under-stood that the button may be made with a circular hub and then the four side walls formed by cutting away portions of the hub, or the button may be made in a die to form 105 the square-ended hub, thus doing away with any cutting action. In the same way, the modified form of button may be stamped

out with the arcuate-form ends of the hub, and the two parallel side faces formed to merge with the arcuate ends.

The button may be formed of metal, and the hub stamped to shape, or if the button is formed of bone, wood or shell, the several contours of the hub may be formed by properly cutting the hub in the desired shape.

Many slight changes might be made without in any way departing from the spirit and scope of the invention.

Having thus described the same, what I claim as new and desire to secure by Letters Patent is:—

- 15 1. A four-hole sew-on button comprising a body portion, a centrally located hub, said hub having at least two parallel faces arranged opposite to each other at the outer end of the hub, the said hub provided with 20 four holes all arranged equi-distant from a central point on the end of the hub and further arranged so that two lines drawn perpendicular to each other through the central point and perpendicular to the sides of the 25 hub will each intersect the centers of two of the said holes, and the said parallel sides adapted to properly guide and position the button in a button attaching machine.

2. A four-hole sew-on button comprising a body having a circular hub, the end of the hub being cut square in cross section, the said hub having four holes extending therethrough and arranged so that if two lines are drawn through a center point on the end of the hub and intersect each other at right angles and extend perpendicular to the sides of the hub, each line will intersect the centers of two of said holes, and the square-ended hub adapted to center and guide the button in its movement to the needles of an automatic button sewing machine.

3. A four-hole sew-on button comprising a body portion, a hub the end of which is square in cross section, said hub provided with four holes therethrough and arranged 45 equi-distant from a central point on the end of the hub, one hole located adjacent each of the four sides of the square midway of its length and the square-sided hub adapted to permit the button to assume one 50 of four positions in a button attaching machine chute and to guide the button in its path to the needle.

In testimony whereof I affix my signature.

FRANKLIN R. WHITE.
